US00D505206S

(12) **United States Design Patent** (10) Patent No.: **US D505,206 S**
Chastain et al. (45) Date of Patent: **** May 17, 2005**

(54) **CONTINUOUS WEARABLE ELECTRODE CONNECTOR ASSEMBLY FOR ECG MONITORING**

(75) Inventors: **David Paul Chastain**, Acton, MA (US); **Matthew D. Abelson**, Boylston, MA (US); **John David Gundlach**, Acton, MA (US); **Scott Chapps**, New York, NY (US); **Gregory R. Madden**, Fort Lauderdale, FL (US); **Kenneth Solovay**, Weston, FL (US)

(73) Assignee: **GMP Wireless Medicine, Inc.**, Fort Lauderdale, FL (US)

(**) Term: **14 Years**

(21) Appl. No.: **29/182,136**

(22) Filed: **May 20, 2003**

(51) LOC (7) Cl. **24-04**

(52) U.S. Cl. **D24/187**

(58) Field of Search **D24/187, 186, D24/168; 600/382, 383, 384, 391, 392, 393**

(57) **CLAIM**

The ornamental design for a continuous wearable electrode connector assembly for ECG monitoring, as shown and described.

DESCRIPTION

FIG. 1 is a top perspective view showing the new design; FIG. 2 is a top plan view thereof; FIG. 3 is a bottom plan view thereof; FIG. 4 is a left side elevational view thereof; FIG. 5 is a right side elevational view thereof; FIG. 6 is a rear elevational view thereof; and, FIG. 7 is a front elevational view thereof.

The broken line showing of ECG monitoring device connector is for illustrative purposes only and forms no part of the claimed design.
